UNITED STATES PATENT OFFICE

2,384,182

POWER OPERATED CLUTCH

Edward G. Lewis, London, Ohio, assignor to The Jeffrey Manufacturing Company, a corporation of Ohio

Application May 25, 1943, Serial No. 488,332

3 Claims. (Cl. 192—85)

This invention relates to a power operated clutch.

An object of the invention is to provide improved hydraulically controlled clutch mechanism either alone or as a part of the feeding mechanism of a mining machine.

Other objects of the invention will appear hereinafter, the novel features and combinations being set forth in the appended claims.

In the accompanying drawings,

Fig. 1 is a side elevational view of a mining machine including the features of my invention;

Fig. 2 is a piping diagram of the hydraulic system incorporated in the machine of Fig. 1;

Fig. 3 is a spread sectional plan view of the drive assembly for the traction means of a mining machine;

Fig. 4 is a sectional view taken on the line 4—4 of Fig. 3 looking in the direction of the arrows; and

Fig. 5 is a transverse sectional elevational view showing a drive sprocket and associated crawler traction chain.

Referring particularly to Fig. 1 of the drawings, there is illustrated a mining machine including a main frame 20 which is provided with an integral or rigidly attached rearwardly extending platform 21 upon which most of the control and operating mechanism is mounted including the electrical driving motor for the mining machine. The main frame 20 provides a truck which is preferably mounted upon traction means which are illustrated in the form of endless crawlers, one of which is seen at 22, there being a pair of such crawlers, one extending longitudinally along each side of the main frame 20.

The position of one of the crawlers 22 with respect to the main frame 20 is illustrated in Fig. 5 of the drawings.

Mounted upon the forward part of the main frame 20 for vertical or upright adjustment is a turntable 23 which carries an endless chain cutter mechanism 24. The turntable 23 is mounted for swinging movement on a tiltable and vertically adjustable ring 25, which ring 25 is supported upon three telescopic double acting hoist cylinders or jacks 26, 126 and 226. (See Figs. 1 and 2.) The hoist cylinders or jacks 26, 126 and 226 are spaced about the periphery of the ring 25 and they are mounted on the main frame 20 as hereinafter described more completely. It may be stated that the construction of the turntable 23, mining mechanism 24 and ring 25 is of a construction which is well known in this art and may follow the construction illustrated in the

5 patent to Nils D. Levin, No. 2,170,927, for a mining machine, dated August 29, 1939, but in the present instance no adjustment between the cutting mechanism 24 and the turntable 23 is provided as is provided in said patent.

It may further be stated that in general the jacks 26, 126 and 226 may be spaced as are the standards 19, 19, 19' of said patent and in general said jacks perform the function performed by said standards 19, 19 and 19' in said patent, but the jacks 26, 126 and 226 possess numerous advantages in connection with the mining machine.

Attention is now directed to Figs. 3, 4 and 5 15 of the drawings and particularly to the gear train for driving the two endless crawlers 22. Mounted on the rear platform is an electric motor 56 (see Fig. 3) which carries on its armature shaft a pinion 57 which meshes with a large gear 58 provided with an integral hub or sleeve 59 which is mounted by means of anti-friction bearings on a stationary shaft 60 carried in spaced uprights rigidly attached to the main frame 20 and platform 21. Feathered on the sleeve 59 is a 20 shiftable gear 61 which is manually operable by gear shifting mechanism 62 to provide a neutral, high speed or low speed drive from the electric motor 56 to the crawlers 22 under the control of individual hydraulically operated friction clutches as hereinafter described.

As illustrated in Fig. 3 of the drawings, the gear 61 is in its neutral position. When shifted to the left, said gear meshes with a large gear 63 to provide a low speed drive. Said gear 63 is keyed to an elongated hub 65 of a pinion 66 which is bushed to rotate freely on a shaft 64. Pinion gear 66 is permanently in mesh with a large gear 67 keyed to a hub of pinion gear 68 which is bushed for free rotation on the stationary shaft 60 and is in mesh with a large gear 69 keyed to the hub of a pinion 70 which in turn is keyed to aforesaid shaft 64 and meshes with a large gear 71 keyed to a main countershaft 72. The above described gear train provides a slow speed drive for the crawlers 22.

It may be pointed out at this time that the aforementioned gear 61 also has integral jaws 73 formed on the right-hand end thereof (as viewed in Fig. 3) which are adapted to engage jaws 74 40 formed integral with the gear 67. By shifting the gear 61 to the right, jaws 73 and 74 are in engagement so that gear 67 is driven directly from gear 58, the gear 61 merely acting as a clutch sleeve. This provides a high speed drive for the crawlers 22. By shifting the gear 61 to the left

from the position viewed in Fig. 3, the low speed drive is effected by introducing a speed reduction between the gear 58 and the gear 61, since reducing gears 61, 63 and 66 are thereby interposed in the drive.

The right-hand or outer end of the shaft 64 is provided with a chain sprocket 75 having on one end jaws of a jaw clutch 76, the other portion of said jaw clutch being keyed to the end of the shaft 64. Said jaw clutch 76 is shiftable into and out of engagement by shifting the sprocket 75 along its axis under the control of manually operable shifting mechanism 77. The sprocket 75 drives an electric cable drum 78 (see Fig. 1) which is mounted on a transverse axis 15 adjacent the rear end of the platform 21.

The countershaft 72 drives the two endless crawlers 22 and each of said endless crawlers is individually controlled by means of a friction clutch and brake, the friction clutch and brake 20 associated with the right-hand drive being designated 79 and that associated with the left-hand drive being designated 80. Since these two types are duplicates, a description of one will suffice for both.

Keyed to the outer right-hand end of the countershaft 72 is a driving inner clutch member 81 which is removably attached to said shaft by a washer and screw designated 82. The driving clutch member 81 is provided with a plurality of axial grooves which receive projections on a plurality of compressible friction clutch plates 83 which are stacked alternately with similar clutch plates having outer projections which are received in axial grooves 84 formed on the inner peripheral surface of a clutch housing or casing 85 which is of generally cylindrical shape and forms not only a clutch housing but also a brake drum by virtue of a centrally disposed outer cylindrical drum surface 86. The housing or casing 85 constitutes the driven member of the clutch 79 as is well understood in the clutch art.

By compressing the clutch plates 83, the frictional driving relation is set up between the driving clutch member 81 and the driven clutch member or housing 85. The particular arrangement of parts, by which this clutch 79 is effectively engaged and disengaged, constitutes an important feature of my invention.

The housing 85 has as an effective part thereof which is removable, an end plate 87 attached to the cylindrical portion of housing 85 by screws 88. Formed as an integral part of said end plate 87 is a cylindrical extension 89 which forms a cylinder of a hydraulic piston motor or actuator 90 for applying and releasing the clutch 79. Said motor 90 includes in addition to the cylinder 89 a piston 91 which on its left-hand end, as viewed in Fig. 3, abuts a crowned boss 92 which is formed on a compressor plate 93 adapted to compress the clutch plates 83 between a peripheral ring thereof and an abutting ring formed on the interior of the housing 85 in alignment therewith. The compressor plate 93 with crowned boss 92 rotates with the casing 85 by virtue of integral webs on the plate 93 extending into the grooves 84. As a consequence there is no relative rotation between the piston 91 and the crowned boss 92 so there is no wear on the bearing surface of either of them.

To provide hydraulic fluid to the interior of the cylinder 89 to actuate the piston 91, said cylinder 89 is provided with an integral head from which an integral post 94 extends. The

post 94 is provided with a longitudinal bore 95 communicating with the interior of the cylinder 89 and at its outer end communicating with one or more radial bores 96 extending through 5 the post 94 and communicating with a circumferential groove 97 which is formed in a removable and stationary sleeve or packing gland 98 which is rigidly attached to a portion of the main frame 20 by a screw 99. Communicating with the circumferential groove 97 is a bore 100 which leads to a hydraulic pipe 101.

To provide a hydraulic seal between the groove 97 and the post 94 while permitting rotation of the post 94, cylindrical extension 89 and clutch housing 85, the sleeve 98 is provided with a pair of hydraulic packings 102, one on each side of a central generally cylindrical portion of the sleeve 98 within which the groove 97 is formed. The sleeve 98 and associated parts are removably attached to post 94 by screw and washer means 103.

As above pointed out, the sleeve 98 is stationary while the combination friction brake drum and clutch housing 85, together with the end plate 87, hydraulic piston motor or actuator 90 and post 94 rotate. Support for these rotated parts is provided first of all by the fact that the left-hand end of the housing 85 is mounted on and keyed to a sleeve 104 which is journaled on the aforementioned countershaft 72 which itself is mounted in spaced journal bearings 105 carried by the main frame 20. This provides support for one end of said clutch 79 and hydraulic fluid motor 90. Additional support therefor is provided by a journal bearing 106 in 35 an upright partition of the main frame 20 which journal bearing 106 receives an outer cylindrical surface formed on the cylinder extension 89.

It is obvious that the conduit and seal construction provided by the bores 95, 96 and 100 and the groove 97, together with the sleeve 98 and packings 102 will provide a conduit or passageway leading from the pipe 101 to the interior of the cylinder 89 so that the piston 91 can be actuated at any time while the hydraulic motor 90 and clutch 79 rotate. Thus the power delivered at either of two selected speeds from the motor 56 to countershaft 72 may be selectively applied or released to drive or release the sleeve 104 under the control of the hydraulic piston motor 90 and the clutch 79.

The sleeve 104 has an integrally formed sprocket 107 which drives a chain 108 which in turn drives a sprocket 109 (see Fig. 5) which is keyed to a sleeve 110 mounted upon spaced journal bearings carried by a stationary shaft 111, which shaft 111 is supported in longitudinally extending plates forming guideways for one of the crawlers 22, said plates being an integral part of the main frame 20, all as clearly illustrated in Fig. 5 of the drawings.

Also keyed to the sleeve 110 is a drive sprocket 112 which meshes with and drives one of the crawlers 22. It is, of course, understood that the structure of the countershaft 72 and the crawler 22 is duplicated on each side of the mining machine, there being an individual clutch and associated hydraulically operating mechanism for each of said crawlers 22. This provides for ready maneuverability of the mining machine, both to move it forwardly and rearwardly and on a curved path in a manner well understood in this art.

As previously mentioned, the housing 85 also provides a brake drum and associated with said housing 85 is a brake band 113 which is operated

by a hydraulic piston motor 114 which is pivotally attached at one end to a plate of the mining machine main frame.

Attention is now directed to Fig. 2 of the drawings which illustrated the hydraulic system of the mining machine. Leading from a hydraulic fluid or oil reservoir 115 is a pipe 116 which communicates with four valves 117 connected in a known manner so as to provide for reverse operation of a hydraulic pump 118 while insuring that regardless of the direction of rotation thereof pipe 119 will always be the pressure or feed pipe. A return pipe 120 is provided for returning hydraulic fluid to the reservoir 115. The pressure of feed pipe 119 leads through a high pressure relief valve 121 and thence to a four-way control valve 122 which preferably has the structure of the control valve disclosed in Fig. 36 of the patent to R. K. Jeffrey et al., No. 2,263,779 for a Mining machine, dated November 25, 1941. This four-way control valve 122 provides for the series operation of the three hydraulic jacks which control the turntable 23, said jacks being designated 26, 126 and 226 in Fig. 2 of the drawings.

It is evident from the above description that only three of the four individual valves of the control valve 22 have been employed to adjust the jacks 26, 126 and 226. The function of the other valve of this group will be explained hereinafter.

Branching from the feed pipe 119 through a check valve 123 is an auxiliary feed pipe 124 leading to and from a pressure oil accumulator 125, the leakage of which drains into the return pipe 120. The auxiliary pipe 124 has branches leading to each of two control valves 127 and 128. It may be stated that the valve 127 provides for the alternate operation of the hydraulic piston motor associated with and operating the clutch 80 or a hydraulic piston motor 214 for operating the brake mechanism associated with said clutch 80. In other words, the valve 127 is so constructed that the clutch 80 and its associated brake mechanism can only be selectively operated and not simultaneously operated.

The construction of the valve 127 may follow the construction of the valve 185 disclosed in Fig. 10 of the application of John S. Beltz, Serial No. 380,812 filed February 27, 1941, entitled "Mining machine," now Patent No. 2,357,724, dated September 5, 1944, or it may have any other desired well-known construction capable of carrying out the above operation.

Similarly the valve 128 provides for the alternate operation of the hydraulic piston motor 80 for actuating the clutch 79 or the hydraulic piston motor 114 for operating the brake mechanism associated with said clutch 79. By virtue of valves 127 and 128 it is evident that both the clutches 79 and 80 may be simultaneously actuated to drive both of the crawlers 22. Also the brake mechanism associated with each of the crawlers 22 may be simultaneously operated. Furthermore, either one of the crawlers 22 may be driven by operating its associated clutch while the other is either free of either braking or driving action or braking action is applied thereto. This latter condition is frequently desired where a sharp turn is to be made with the mining machine.

Returning to the four-way valve 122. As was above pointed out, these four valves provide a series relation and normally they provide a no

load by-pass for the pump 118 so that practically no pressure is present in the pipe 119 when none of the individual valves of four-way valve 122 is actuated. It is for this reason that the accumulator 125 is provided because it may be desirable to operate the clutches or the brakes while the no load by-pass is provided for pump 118. However, should all of the oil be drained from accumulator 125 and thus none be available to operate one or more of the brakes or clutches and such operation was desired, I provide the fourth individual valve of the unit 122 so that by the simple expedient of operating this valve the no load by-pass for the pump 118 is shut off and since the oil in pipe 119 which has been by-passed has no place else to go it will flow to the accumulator 125 and this can be allowed to continue until it is full which would be indicated by the operation of the high pressure relief valve 121.

By reference to Fig. 1 of the drawings, three operating handles designated as a group by the reference character 129 are provided. These are the operating handles for the three individual valves of the four-way control valve 122, one for each of the jacks 26, 126 and 226. A knob 130 adjacent the handles 129 provides the operating means for the by-pass shut-off valve which is the fourth individual valve of the four-way control valve 122.

The mechanism for propelling or feeding the mining machine provides for its propulsion at a high or transportation speed so that it can readily move from one room to the next or toward and from the working face at a high rate. The low speed drive provides for feeding of the machine while it is cutting a kerf by rectilinear or curved feeding movement as controlled by the traction means 22. The individual friction clutches are not only individually hydraulically operated by individual hydraulic motors but these motors are mounted or formed as a unit with their associated clutches and rotated with the housing or driven members thereof. This makes for a compact and efficient arrangement of clutches and hydraulically operating mechanism and a point of particular significance is that there is no relative rotation between the actuating piston such as the piston 91 and the crowned boss 92 of the compressor plate 83 so there is no occasion whatever for wear between any part of the hydraulic piston motor 80 and the clutch 79. This is an important feature of my invention.

Obviously those skilled in the art may make various changes in the details and arrangement of parts without departing from the spirit and scope of the invention as defined by the claims hereto appended, and I wish therefore not to be restricted to the precise construction herein disclosed.

Having thus described and shown an embodiment of my invention, what I now desire to secure by Letters Patent of the United States is:

1. A combination friction clutch and hydraulic motor actuating means therefor including driving and driven clutch members one of which includes a rotary mounted housing having an end plate, said end plate having an integral part forming a cylinder of the clutch actuating motor, said cylinder having its axis aligned with the axis of said housing, a piston in said cylinder, a clutch compressor plate in said housing having a central crowned boss, said piston having an abutting relation with said crowned boss, and means for supplying fluid pressure to said cylinder.

der thereby to force said piston against said crowned boss and engage said clutch members.

2. A combination friction clutch and hydraulic motor actuating means therefor including driving and driven clutch members one of which includes a rotary mounted housing having an end plate, said end plate having a part forming a cylinder of the clutch actuating motor, a piston in said cylinder, a clutch compressor plate in said housing having a central crowned boss, said piston having an abutting relation with said crowned boss, and means for supplying fluid pressure to said cylinder thereby to force said piston against said crowned boss and engage said clutch members.

3. A combination friction clutch and hydraulic motor actuating means therefor including driving and driven clutch members one of which includes a rotary mounted housing having an end plate, said end plate having a part forming a cylinder of the clutch actuating motor, a piston in said cylinder, a clutch compressor plate in said housing having a central boss, said piston having an abutting relation with said boss, and means for supplying fluid pressure to said cylinder thereby to force said piston against said boss and engage said clutch members.

EDWARD G. LEWIS.
